E. POOLE.

CARPET.

No. 18,764.

Patented Nov. 27, 1888.

UNITED STATES PATENT OFFICE.

EDWARD POOLE, OF BROOKLYN, NEW YORK, ASSIGNOR TO THE LOWELL MANUFACTURING COMPANY, OF LOWELL, MASSACHUSETTS.

DESIGN FOR A CARPET.

SPECIFICATION forming part of Design No. 18,764, dated November 27, 1888.

Application filed October 13, 1888. Serial No. 288,026. Term of patent 3½ years.

To all whom it may concern:

Be it known that I, EDWARD POOLE, of the city of Brooklyn, county of Kings, and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a body part, A, and a border, B.

What I claim as new, and desire to secure by Letters Patent, is—

1. The design for carpets, consisting of the 20 body part A, substantially as shown.
2. The design for carpets, consisting of the border B, substantially as shown.
3. The design for carpets, consisting of the 25 body part A and the border B, substantially as shown.

EDWARD POOLE.
